(57) **CLAIM**

The ornamental design for a party light, as shown and described.

DESCRIPTION

FIG. 1 is a front perspective view of a party light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 1.

The broken lines in the drawings illustrate the portions of the party light, which form no part of the claimed design.

The dash-dot-dash broken line defines the boundary of the enlarged views and form no part of the claimed design.
